CLAIM

The ornamental design for a recovery barge, as shown and described.

DESCRIPTION

FIG. 1 is a front top left side perspective view of the recovery barge with the retractable outriggers in a fully retracted position.

FIG. 2 is a back bottom left side perspective view of the recovery barge with the retractable outriggers in a fully retracted position.

FIG. 3 is top view of the recovery barge with the retractable outriggers in a fully retracted position.

FIG. 4 is a bottom view of the recovery barge with the retractable outriggers in a fully retracted position.

FIG. 5 is left side view of the recovery barge with the retractable outriggers in a fully retracted position.

FIG. 6 is a right side view of the recovery barge with the retractable outriggers in a fully retracted position.

FIG. 7 is a front view of the recovery barge with the retractable outriggers in a fully retracted position.

FIG. 8 is a back view of the recovery barge with the retractable outriggers in a fully retracted position.

FIG. 9 is a front top left side perspective view of the recovery barge with the retractable outriggers in a fully extended position.

FIG. 10 is a back bottom left side perspective view of the recovery barge with the retractable outriggers in a fully extended position.

FIG. 11 is top view of the recovery barge with the retractable outriggers in a fully extended position.

FIG. 12 is a bottom view of the recovery barge with the retractable outriggers in a fully extended position.

FIG. 13 is left side view of the recovery barge with the retractable outriggers in a fully extended position.

FIG. 14 is a right side view of the recovery barge with the retractable outriggers in a fully extended position.

FIG. 15 is a front view of the recovery barge with the retractable outriggers in a fully extended position; and,

FIG. 16 is a back view of the recovery barge with the retractable outriggers in a fully retracted position.

The broken lines are for the purpose of illustrating portions of the recovery barge that form no part of the claim.
